INVENTOR
Myer Sigman,
By C. Wm. Brown & Crampton,
His atty's.

UNITED STATES PATENT OFFICE.

MYER SIGMUN, OF CLEVELAND, OHIO.

HEATER FOR AUTOMOBILE-RADIATORS.

1,321,482.

Specification of Letters Patent. Patented Nov. 11, 1919.

Application filed February 1, 1917. Serial No. 145,909.

To all whom it may concern:

Be it known that I, Myer Sigmun, a citizen of the United States, and a resident of Cleveland, in the county of Cuyahoga and State of Ohio, have invented a certain new and useful Heater for Automobile-Radiators; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to heating means for the radiators of automobiles to prevent a freezing of the same and also to maintain a circulation within the water cooling system of an automobile engine when the same is at rest.

The object of my invention is the provision of an improved device of this character which is simple, cheap and inexpensive in its construction and which may be used without danger of fire.

The invention is described in the following specification, and while, in its broader aspect, it is capable of embodiment in numerous forms, a preferred embodiment thereof is illustrated in the accompanying drawings, in which—

Figure 1 is an elevation of a portion of an automobile with my invention connected to the cooling system of the engine. Fig. 2 is an enlarged elevation of the heater with a part broken away. Fig. 3 is a section on the line 3—3 in Fig. 2, and Fig. 4 is a perspective view of the electric heating element removed from the heater.

Referring to the drawings, 1 designates an automobile engine of the internal combustion type, 2 the customary radiator and 3 the heater embodying my invention, which 45 heater is attached to the engine casing or otherwise suitably mounted in position to be interposed in the water circulating system between the radiator and the engine.

The heater 3 comprises a drum which may 50 be of circular, elliptical or other form in cross section, and has an internal casing 4 which cooperates with the external casing 5 to form a water circulating chamber 6. The central opening or passage 7, which is 55 formed by the inner casing 4, is open at top and bottom thereof to permit a circulation

of air therethrough, and a suitable heating means 8 is disposed therein. The heating means 8, in the present instance, comprises an electric heating element, which is supported in suspended relation within the passage 7 by a top plate 9, which rests on and is screwed or otherwise suitably secured to the upper end of the drum. The lower end of the heating element is provided with laterally projecting spring fingers or flanges 10, which engage the opposite side walls of the passage 7 and prevent lateral movements of the heating element in said passage.

The outlet manifold 11 of the water circulating system, which manifold is in communication with the water jacket space of the engine cylinders, is connected to the upper end of the radiator 2 through the medium of the upper end portion of the heating drum chamber 6 and a flexible tube 12, said tube being preferably split and having one portion connected to the interior of the heating chamber 6 through the medium of 80 a nipple 13 on the drum and the other portion of said tube, which forms the outlet from the chamber, being connected to a nipple 14 of the drum. The intake water circulating manifold 15 for the engine cylinders has 85 connection with the interior of the drum chamber 6 at the lower end thereof through a nipple 16, and a flexible tube 17 opens communication between the lower end portions of the radiator 2 and drum chamber 6, being connected to a nipple 18 at the lower end 90 of the heating drum.

It is evident that a generating of heat within the drum passage 7 will cause a heating of the water within the drum chamber 6 95 and create a forced circulation of the water through the circulating system. A material advantage is obtained by interposing the water chamber 6 of the drum in both the outgoing and ingoing passages of the engine 100 circulating system, as this, under ordinary conditions, will create a circulation through the entire circulating system, namely, the engine, the radiator and the connecting passages, or if the circulation in either the radiator or the engine should happen to be stopped an independent circulation is set up through the other member. For instance, should circulation through the radiator be stopped from any cause, the heating 110 of the water within the heater chamber 6 will cause a circulation to take place through

the engine, so as to prevent freezing therein and a consequent cracking of the engine casing.

If an electric heater is used an electric plug may be inserted into a socket 19 on the plate 9.

It is evident that the heater may be removed from the engine during warm weather and the radiator tubes 12 and 17 connected directly to the respective engine manifold.

I wish it understood that my invention is not limited to any specific construction, arrangement or form of the parts, as it is capable of numerous modifications and changes without departing from the spirit of the claim.

Having thus described my invention, what I claim as new, and desire to secure by Letters Patent, is—

The combination with a radiator and an internal combustion engine of an automobile, in water circulating communication one with another, of a drum having an internal

heating chamber open at its top and bottom, 25 and surrounded with a water circulating chamber having its top portion provided with an opening in connection with the outlet of the engine circulating system and also having an opening in communication with 30 the upper portion of the radiator, the lower end of said water chamber having an opening in connection with the inlet of the engine water circulating system, and having an opening in communication with the lower 35 end of the radiator, whereby water may circulate between the engine and radiator, or independent circulation may be set up through the engine and water chamber and through the radiator and water chamber, 40 and an electric heating unit removably disposed in the inner chamber of said drum and closing the top opening of said heating chamber.

In testimony whereof, I have hereunto 45 signed my name to this specification.

MYER SIGMUN.
